COMBINED PREHEATING AND MIXING CHAMBER FOR LIQUID-FUEL BURNERS

Original application filed August 27, 1926, Serial No. 131,868. Divided and this application filed
September 15, 1926. Serial No. 135,518.

This invention relates to a combined preheating and mixing chamber for liquid fuel burners.

The object of the present invention is the provision of a combined preheating and mixing chamber of a novel and compact design and which is preferably fixedly positioned with reference to the burner manifold so as to present an efficient mixing chamber for mixing and delivering the vaporized fuel to the manifold. A further feature of this combined preheater and mixing chamber resides in the provision of a preheater element which is pivotally mounted in the mixing chamber 15 casing and which preheating element is designed to be moved into one position to act as a novel preheater, and into another position to form a part of the housing for the mixing chamber. This novel arrangement of 20 parts makes it possible to form the burner and manifold elements stationary and to move the vaporizing tube as a unit relatively thereto, said vaporizing tube having a useful function in a plurality of different positions 25 due to its cooperation with the combined preheating and mixing chamber.

Another feature of this invention relates to the novel form of the pivotally mounted preheater member, said member being adapted to be moved to open position to cooperate with the end of the generating tube to initially start the burner, or stove, and cooperating with the mixing chamber when the tube is moved to normal supplying position to serve 35 a useful function in directing the resulting gases. When the pivoted preheater member is moved to open position it also serves as a flame deflector for both deflecting the flames backwardly against the vaporizer tube and 40 also upwardly around the same.

This application is a division of application No. 131,868 filed on the 27th day of August, 1926.

In the drawings:

45 Fig. 1 is a perspective view of our novel combined preheating and mixing chamber, and showing the preheating element in upright open position preparatory to serving as a preheating means for the generator tube.

50 Fig. 2 is a longitudinal section through

the combined preheating and mixing chamber in combination with a vertical section through a stove unit embodying this preheating and mixing means, the combined preheating and mixing chamber being shown 55 in closed position.

Fig. 3 is a vertical sectional view similar to Fig. 2 showing the positioning of the various parts of a complete stove unit embodying my preheating and mixing means and also 60 showing the relative positions of the generator tube and preheating member preparatory to initially starting the stove.

Fig. 4 is a section taken on line 4—4 of 65 Fig. 3.

Fig. 5 is a sectional view taken on line 5—5 of Fig. 3, and illustrating the two coils of wire and a plurality of the relatively enlarged annular passageways for the fuel or gases in 70 the enlarged portion of the generating tube.

The novel combined preheating and mixing chamber forming the subject matter of this invention may be utilized with various types of stove and burner structures of the liquid fuel type, and the preferred embodiment of such combined preheating and mixing chamber with a stove structure, wherein the various parts cooperate in a novel manner is described and claimed in said pending application No. 131,868 of which this 75 is a division.

This combined preheating and mixing chamber may be generally designated 1 and preferably comprises an integral cast housing formed to present a plurality of passageways for both the conduction of the vaporized fuel and for the conduction of air to be mixed with the fuel. This housing element is best shown in Fig. 1, and as shown, is peculiar and novel in shape in that it is designed for use with a particular stove structure. However, in general form this housing of the mixing chamber is formed to present a passageway 2 for conducting the mixed gases and air to any suitable manifold, which may be here designated 3. This passageway 2 preferably extends horizontally and then is enlarged and extends rearwardly and upwardly, as at 2^a, to form a chamber or housing for receiving the mixed vaporized fuel and air. The 100

housing is cored transversely, as at 4, to provide an air entrance passageway, and is also centrally cored, as at 5, to present an L-shaped passageway for conducting the air from the entrance 4 upwardly to a meeting point with the vaporized gases.

A part of the housing for receiving the generator may be called the entrance head and may be designated 6. This entrance head 6, in addition to forming the upper part of the passageway 5, is also provided with a suitable aperture 7 for receiving the enlarged end 8 of a suitable generator tube. This entrance head 6 is also provided with suitable oppositely disposed auxiliary air ports 9 which are positioned just in front of the jet block 10 of the generator tube when such jet block is in normal operating position, as is shown in Fig. 2.

The upper part of the housing 1 is open, as best shown in Fig. 1, and the sides of the housing which form this opening are preferably of such width and of finished surface so as to receive the preheater member, which may be generally designated 11, as will be presently described. A filler block 12 is preferably mounted within the housing 1 to restrict the passageway 2^a to a predetermined size proportionate to the correct quality of fuel mixture desired. The sides of the housing 1 for receiving and cooperating with the preheater member may be designated 13 and are preferably finished on their upper interior sides. The entrance head 6 of the housing is preferably tapered at its forward sides, as is clearly shown in Figs. 1 and 2, and the portion 14 thereof is machine finished complementally with the tapered machine finished portion 15 of the preheater.

This preheater is preferably L-shaped, as best shown in Fig. 3, and is designed to be pivoted to the housing 1, as at 16. The lower leg of this L-shaped member 11 is preferably formed to provide a suitable and relatively shallow drip pan 17, and the rear end of this drip pan, or the portion joining the two legs of the L-shaped preheater is preferably formed with an arcuate depression 18, and this depression is so designed and predetermined relative to the pivot 16 and the axis of the aperture 7 as to perform a definite useful function. In other words, the top portion of this arcuate deflector 18 is aligned with the orifice of the jet block 10, whereby the vapor issuing from the generator and jet block under pressure will strike the portion 18 and will be redirected downwardly and backwardly against the exterior of the generator, the gases from the generator combining with the air to form a combustible mixture before striking the deflector member 18.

The lower leg 17 of this preheater member is provided with a suitable wire mesh, or absorbing member 19, which is so positioned as to hold a suitable quantity of liquid fuel

through the capillary action of the wire mesh, and is also positioned longitudinally and transversely of the portion 17 so as to deflect and guide the flames which are redirected by the portion 18 upwardly and around the enlarged portion of the generator tube, when in its preheating position. This lower leg 17 is designed to fold back against the wall of the housing 1 when the preheater member is moved to closed position, as shown in Fig. 2.

The upper leg of this preheater member 11 is preferably U-shaped in cross section and of sufficient length that the machine tapered surfaces 15 cooperate with and contact with the machined surfaces 14 to present a relatively tight fit when the preheater member is moved to closed position, as shown in Fig. 2. The sides of this upper leg are preferably machined on the exterior surfaces whereby they cooperate with and contact with the machined sides 13 of the housing 1, whereby when the preheating member is moved to closed position the complete mixing chamber will be formed and the sides and end of the member 11 will so contact with the complementary parts of the housing as to form relatively tight joints to insure the maintenance of a predetermined quality of mixture. The U-shaped formation of this upper extension of the preheater member also serves an additional function in that it creates a draft for the burning fuel during the preheating operation and thus causes the flames from the pan 17, and the redirected flames from the compression 18 to pass upwardly and around the enlarged portion of the generator tube.

This combined preheating and mixing chamber is preferably adapted for use with stoves of the type wherein the generating tube is positioned above a burner, or burners, supplied with the generated gases. In the present embodiment, a suitable burner is shown, as at 20, and forms a part of the manifold which is designated 3. While the combined preheating and mixing chamber is preferably designed to operate in combination with the novel type of manifold, yet it will be obvious that such preheating and mixing chamber may be utilized with any type of manifold. Both the manifold, burner, or burners, and the combined preheating and mixing chamber are preferably stationarily mounted, as best shown in Fig. 3.

The fuel container, or tank, for supplying the liquid fuel may be designated 21, and the generator tube is preferably rigidly mounted thereon, as shown in Fig. 3. This generator tube is of novel construction in that it is provided with the enlarged portion 8, and a normal small sized portion 22. This generator tube preferably has screw fitting relation with a suitable valve housing 23, whereby the liquid fuel is emitted or shut off from the generator tube at the rear end thereof, or in other words, at the valve hous-

ing 23. A suitable rod 24 extends the length of the generator tube and is provided at the end thereof with a suitable cleansing wire for keeping the orifice of the jet block clean.

5 A suitable coil wire 25 surrounds and extends the length of this rod 24, whereby to restrict and at the same time insure positive feeding of the liquid fuel and gases by capillary action. A second coiled wire 26 is positioned around the coiled wire 25 and extends the length of the enlarged portion 8 of the generating tube. This coil 26 insures the feeding of the liquid fuel and vapor in a much larger annular helical column whereby a 10 greater area and amount of liquid fuel is presented to the initial heating flames for causing preheating in the generator tube. This relatively enlarged part of the generator tube has also an additional function, as will 15 be presently described.

The fuel feeding unit which includes the container and generator tube is adapted to be slidably mounted relative to the rigidly positioned burner, manifold and mixing chamber, and in Fig. 3, I have shown this fuel feeding unit as being provided with suitable runways 27 which are adapted to be slidably supported by suitable supporting guides 28 which, as shown, are mounted and 20 supported by a casing 29 which forms the exterior case for the entire stove unit. The central burner 20 is preferably provided with a suitable radiating and deflecting shield 30, and the forward part of this shield is adapted 25 to predetermine the inward position of the fuel feeding unit by contacting with the heat shield 31 mounted upon the fuel feeding unit. The fuel feeding unit may be slidably moved from its innermost position, as shown 30 in Fig. 3, to its outer normal operating position, and when in its outermost position it is adapted to be automatically locked by means of the gravity pawl 32 which locks the unit, and particularly the jet block 10, 35 in the position shown in Fig. 2, which is the normal preferred operating position to obtain the desired mixture of air and vaporized fuel.

The enlarged portion 8 of the generator tube is adapted to be positioned either above the preheating flame from the preheater 17, or above the burner 20 for continuous operation. The entire burner therefor is made of a sufficient size, and this is obtained mainly 50 by enlarging the end of the tube, to hold a predetermined amount of liquid fuel, which amount of fuel is sufficient to, when ignited, to preheat the tube to a sufficient extent to efficiently cause vaporization of any additional fuel fed into the tube.

In the initial preheating operation the fuel feeding unit and the generator tube being in the position shown in Fig. 3, the upper leg 11 of the preheater unit is then raised to 55 the position shown in Figs. 1 and 3. The

valve in the valve housing 23 is then opened until the generator tube is filled and a small amount of the fuel drops down and is absorbed or held in suspension by the member 19. This having been done, it is only necessary to ignite the fuel in the drip pan 17 whereby the flames therefrom will be initially drawn around the enlarged end of the generator tube. The generator tube being 60 so enlarged to present a relatively large heating area, the heat from the open flame will quickly cause vaporization of some of the fuel referred to, and the resulting pressure will cause some of the gases to be emitted from the jet block. These emitted gases will be 65 instantly ignited and the resulting flames will strike the arcuate portion 18 and be redeflected backwardly and upwardly against and around the enlarged portion 8 of the tube. This results in a positive blast action of the 70 flames so as to quickly and efficiently heat the enlarged end of the generator tube. Before, or after all of the fuel has been vaporized and ejected from the generator tube, the preheater member 11 may be moved downwardly 75 into the position shown in Fig. 2.

When this is done the stove is ready for normal operation and the fuel feeding unit may be then moved to its outward position which corresponds with the position shown 80 in Fig. 2, and the valve 23 opened to admit liquid fuel to the heating generator tube. This fuel striking the generator tube will be instantly vaporized and this vapor 85 emitted under pressure from the jet block 10. These emitted gases passing the air intakes 5 and 9 will draw in a sufficient amount of air to produce a combustible mixture, and which mixture will be conducted through the 90 passageways 2^a and 2 to the manifold 3. Part of these gases then pass to the burner 20 where they may be ignited to continuously 95 heat the enlarged portion 8 of the generator, as shown in Fig. 2 whereby the vaporization of the liquid fuel is continuously maintained 100 as long as desired. As shown in Figs. 2 and 3, it will be understood that the pivoted preheater member 11 may be slidably supported 105 by one of the grates of the stove and such 110 grate suitably pivoted or otherwise mounted, whereby it is only necessary to move the 115 grate up or down to move the preheater member 11 into preheating position or into normal operating position to form a part of the 120 mixing chamber.

Although it is not necessary, the head 6 of the mixing burner housing is preferably provided with suitable grooves 35 which extend along each side thereof and which are 125 adapted to receive suitable deflector shields 36 whereby to form suitable channels for the passage of the air to the apertures 9 and also to form shields at the lower end thereof for guarding the passageway 4, 130

whereby to maintain a uniform feeding of air to both the passageways 5 and 9.

What we claim is:—

1. A combined preheating device and mixing member for liquid fuel burners, comprising a housing for receiving a generating means and provided with a passageway for conducting the generated gas to the burner manifold, and including means positioned within the housing and movable to close said passageway, and for forming a preheating device for the generating means.

2. A combined preheating device and mixing chamber for liquid fuel burners, comprising a housing adapted to cooperate with a generating member for conducting the generated fuel towards the burner, or burners, a part of said housing being movable and provided with a fuel pan adapted to be positioned adjacent the generating unit.

3. A combined preheating device and mixing chamber for liquid fuel burners, comprising a housing adapted to receive a generating member, a part of said housing forming a fuel pan for providing flames for heating up said member and a chimney for directing flames around said member.

4. A combined preheating device and mixing chamber for liquid fuel burners, comprising a housing adapted to receive a generating member, and including means movable to one position to form a fuel pan for preheating the member and to another position for closing the housing to conduct the generated gases to the burner, or burners.

5. A combined preheating device and mixing chamber for liquid fuel burners, comprising a housing provided with an entrance head for receiving a generating member, said head being provided with a plurality of air passageways, and means movable into tight fitting relation with said head to close said housing and form a wall of a passageway for conducting the combined gas and air mixture to the burner, or burners.

6. A combined preheating device and mixing chamber for liquid fuel burners, comprising a housing provided with a passageway for conducting the fuel to a burner or burners, and a fuel pan pivotally mounted in said housing and adapted to be moved to open or close said passageway.

7. A combined preheating device and mixing chamber for liquid fuel burners, comprising a housing adapted to receive a movable generator member, and means movable within the housing to a position in front of the generator member for directing the ignited gases initially issuing from said member rearwardly against said member to accelerate initial preheating and starting of the same.

8. A mixing chamber for liquid fuel burners, comprising a housing member provided with a passageway for conducting gener-

ated gases to a burner, or burners, and a unit cooperating with said housing and comprising one part movable into complementary relation with said housing to complete the same, and also comprising another part movable into position to serve as a preheating member.

9. A combined preheating device and mixing chamber for liquid fuel burners, comprising in combination a conduit adapted to receive the outlet of a generator member and for conducting vaporized fuel from said generating member to the burner or burners, and a pivotally mounted flame deflector within the conduit and movable to a position in front of said generating member whereby to initially deflect the vaporized fuel issuing from said member back against said member in the form of flames to accelerate the starting thereof.

10. A starting device for liquid fuel burners having a generator tube and a conduit for mixing and conducting the vaporized fuel towards the burner manifold, comprising a blast deflector horizontally pivoted and vertically movable within the conduit, said blast deflector being movable to one position to deflect the vaporized fuel, issuing from the generator tube, back against the generator tube to accelerate starting, and movable to another position to allow the generated fuel to pass through the conduit.

11. A starting device for liquid fuel burners of the type having a generating tube provided with a valve at its inlet end and a conduit for mixing and conducting the vaporized fuel from the generating tube towards the burner manifold, comprising a combined blast deflector and fuel pan movable as a unit within said conduit to a position in front of and directly beneath the outlet end of the generating tube, the fuel pan producing flames for heating up said tube, and the blast deflector deflecting vaporized fuel issuing from said tube back against the same in the form of flames to accelerate the heating of said tube.

12. A starting device for liquid fuel burners of the type having a single main generator, and a conduit for conducting the vaporized combustible fuel from the generating tube towards the burner or burners, comprising a blast deflector positioned adjacent the end of the generating tube, and means for effecting relative axial movement between the generating tube and blast deflector whereby the blast deflector will be positioned in front of the generating tube, said blast deflector having a portion shaped for deflecting the vaporized fuel issuing from the generating tube backwardly in the form of a blast of flame against the tube itself.

13. That step in the starting of a liquid fuel generating apparatus of the type having a main generating tube, a tank for sup-

plying liquid fuel to the generating tube under pressure, and a conduit for conveying the vaporized fuel in a main path towards the burner or burners, which comprises collecting a stationary body of liquid fuel in the generator and below the generator, igniting the body of liquid fuel below the generator to heat the same, and vaporizing the liquid in the generator, initially deflecting the vaporized fuel from its normal path, and directing the vaporized fuel in the form of a blast of flame directly against the main generating tube to accelerate vaporization of the liquid fuel in the tube and the starting of the apparatus and then turning on the normal supply of liquid fuel under pressure to permit the same to flow into the heated generator tube.

14. The method of starting a liquid fuel generating apparatus of the type having a generating tube with a valved inlet, a mixing chamber and tank for supplying liquid fuel to the generator, which comprises filling the generator tube and turning off the said valve, and then initially heating the same to start vaporization of the fuel, causing a portion of the vaporized fuel to issue from the generator tube, and intercepting said initially vaporized fuel and deflecting the same backwardly and directly against the generating tube in the form of flames to accelerate vaporization of the liquid fuel in the generator tube and the starting of the apparatus before turning on a continuous supply of liquid fuel from the tank to the generator.

15. Starting and mixing structure for liquid fuel burners, comprising a mixing chamber housing having an entrance head for receiving air and vaporized fuel and forming a passageway for conducting the mixture of air and fuel towards the burner manifold, a priming cup positioned adjacent to and in alignment with said entrance head, and a generating tube axially slidable through said entrance head and to a position above said priming cup to effect starting.

16. A combined starting and mixing device for liquid fuel burners, comprising in combination a mixing chamber housing having an entrance head adapted to receive the outlet of a generator member and being provided with a passageway for conducting vaporized fuel from said generator member to the burner or burners, one of which being positioned adjacent said generator tube, a blast deflector positioned adjacent said entrance head and in alignment with said generating tube, said generating tube being slidably axially through said entrance head and to a position adjacent the blast deflector, whereby said blast deflector will deflect vaporized fuel issuing from the generator tube backwardly in the form of a blast against the tube itself to accelerate starting.

17. A combined starting member and mix-

ing chamber for liquid fuel burners, comprising a housing member provided with a passageway for conducting vaporized fuel to a burner or burners, an entrance head for receiving a movable generating tube, and a unit 70 cooperating with said housing and comprising one part movable into complementary relation with said housing to complete the same and another part cooperating with the end of the generating tube and adapted, as a result of relative movement between said part and generating tube, to be positioned in front of the generating tube to serve as a blast deflector and preheating member.

18. That step in the starting of liquid fuel generating apparatus of the type having a main generating tube, a tank for supplying liquid fuel to the generating tube under pressure, and a conduit for conveying the vaporized fuel in a main path towards the burner 80 or burners, which comprises filling the generator tube with liquid fuel and allowing some of the fuel to collect in a body beneath the end of the generator tube, closing off the supply of liquid fuel, igniting the body of fuel 85 beneath the generating tube whereby the same will heat the fuel in the generator tube to partially vaporize the same and form a pressure in the generating tube, and then initially deflecting the vaporized fuel initially projected from the generating tube from its normal path and directing such vaporized fuel in the form of a blast of flame directly against the end of the main generating tube to accelerate 90 vaporization of the liquid fuel in the tube and the starting of the apparatus.

19. That step in the starting of liquid fuel generating apparatus of the type having a main generating tube, a tank for supplying liquid fuel to the generating tube under pressure, and a conduit for conveying the vaporized fuel in a main path towards the burner or burners, which comprises filling the generator tube with liquid fuel and allowing some of the fuel to collect in a body beneath the end of the generator tube, closing off the supply of liquid fuel, igniting the body of fuel 105 beneath the generating tube whereby the same will heat the fuel in the generator tube to partially vaporize the same and form a pressure in the generating tube, and then initially deflecting the vaporized fuel initially projected from the generating tube from its normal path and directing such vaporized fuel in the form of a blast of flame directly against the end of the main generating tube to accelerate 110 vaporization of the liquid fuel in the tube and the starting of the apparatus, and then removing the deflecting means and supplying liquid fuel to the generating tube whereby 115 vaporized fuel will be conducted to the main conduit to supply the burner or burners.

20. The method of starting liquid fuel generating apparatus of the type having a generating tube with a valve inlet and a relatively 120

free outlet, and a mixing chamber and tank for supplying liquid fuel to the generator, which comprises filling the generator tube and allowing some of the liquid fuel to accumulate in a body beneath the end of the generator tube and then turning off the supply of fuel, igniting said accumulated liquid fuel to heat the end of the generator tube whereby to vaporize a portion of the fuel in the generator tube and cause the same to be ejected under pressure, then intercepting said initially vaporized fuel and deflecting the same backwardly and directly over the body of fuel and against the generating tube in the form of a blast of flame to accelerate the burning of the exterior body of fuel and the vaporization of the liquid fuel in the generator tube and then turning on said valve to allow the liquid fuel to flow freely into said tube.

20 In testimony whereof we affix our signatures.
